UNITED STATES PATENT OFFICE

149,465

DESIGN FOR A RACK FOR NURSING
BOTTLES OR THE LIKE

Edward Adler, New York, N. Y.

Application January 16, 1947, Serial No. 136,179

Term of patent 7 years

(Cl. D33—3)

To all whom it may concern:

Be it known that I, Edward Adler, a citizen of the United States of America, residing in the city, county, and State of New York, have invented a new, original, and ornamental Design for a Rack for Nursing Bottles or the like, of which the following is a specification, reference being had to the accompanying drawing, forming a part thereof.

Fig. 1 is an elevational view of a rack for nursing bottles or the like showing my new design;

Fig. 2 is a top plan view thereof; and

Fig. 3 is a side elevational view thereof.

I claim:

The ornamental design for a rack for nursing bottles or the like as shown.

EDWARD ADLER.
